(57) **CLAIM**

The ornamental design for a jar, as shown and described.

DESCRIPTION

FIG. 1 is a top, front perspective view of a jar showing my new design;

FIG. 2 is a front elevational view thereof, the rear elevational view being identical;

FIG. 3 is a right side elevational view thereof, the left side elevational view being identical;

FIG. 4 is a bottom plan view thereof; and,

FIG. 5 is a top plan view thereof.

The oblique shade lines shown in the drawings represent transparent surfaces.
